2,207,842

METHOD OF AND APPARATUS FOR
STAPILIZING YARNWilliam Whitehead, Rye, N. Y., assignor to
Celanese Corporation of America, a corporation
of Delaware

Application March 2, 1939, Serial No. 259,440

13 Claims.

(Cl. 19—1)

The present invention relates to the manufacture of textile yarns and relates more particularly to the production from continuous filament yarns of yarns having the appearance of spun yarn, i. e., yarn made from staple fiber.

In the manufacture of spun yarn from artificial fibers, the usual practice is to cut continuous artificial filaments or waste filaments into comparatively short lengths, for example, lengths of

10 1½ to 2" or more, and then subject the staple fibers produced to a series of operations appropriate to the length of the fiber, such operations being similar to those accorded natural fibers such as cotton or wool, including opening, carding,

15 drawing and spinning. These operations represent considerable expense in the production of such yarns, since they involve a relatively slow transformation of the initial fibrous material to a finished yarn.

20 An object of the present invention is the expeditious and economical production of yarns containing the staple fibers from yarns composed of continuous filaments.

25 Another object of this invention is the production of stiplized yarns by bringing a filamentary yarn into intermittent contact with a moving cutting element for cutting at least some of the filaments at intervals along the length of the yarn.

30 A further object of this invention is the provision of a novel device for converting a yarn of continuous filaments into a staple fiber yarn without the necessity of cutting or breaking continuous filament yarn to short lengths and then spinning the fibers thus produced.

35 Other objects of this invention, together with certain details of construction and combinations of parts, will be described in the following description and in the claims.

40 In accordance with this invention, a continuous filament yarn is subjected to the action of an abrasive cutting means between which and the yarn there is relative rotary movement so as to break the continuity of the filaments of the

45 yarn, whereby upon being twisted the resulting yarn resembles spun fibrous yarn. The cutting operation is so carried out that at any point any one or relatively few filaments of the yarn are cut or broken, or at least some of the filaments 50 remain uncut or unbroken, so that the continuity of the bundle as a whole is maintained.

The cutting of the individual filaments of the yarn may be carried out in a regular or irregular manner depending upon the degree of filament cutting required and upon the characteristics

of the yarn involved. It will be appreciated that in order to impart a uniform appearance along the length of the yarn, the cutting of the filaments should be carried out in a regular manner. Conveniently, the cutting operation is carried out during a twisting operation performed on the yarn, and preferably in such a manner that a certain amount of twisting-in of the cut or broken filament ends occurs.

5 Preferably the cutting of the filaments of the yarn is effected during a twisting operation with the abrasive cutting means arranged to engage the yarn as it proceeds from the supply package to the take-up device, the supply package being mounted on a rotating twisting spindle.

10 While the present invention is particularly concerned with processing yarns of continuous synthetic filaments such as, for example, organic derivatives of cellulose and particularly cellulose acetate, it may also be applied to natural yarns such as silk, and also to the processing of yarns comprising or made up from discontinuous filaments or fibers in which case the fibers in the 15 yarn are cut into smaller lengths. The present invention may also be used on mixed or compound yarns comprising different twists, plies or origins.

20 Referring now to the drawing wherein the preferred embodiments of apparatus for carrying out my invention are shown:

25 Figure 1 is a view, partly in section, showing one application of the device of my invention,

Figure 2 is a plan view of the showing in Figure 1,

30 Figures 3, 4 and 6 are views showing modified applications of my device, and

35 Figure 5 is a view taken along line 5—5 in Figure 4 looking in the direction of the arrows.

Like reference numerals indicate like parts throughout the several views of the drawing.

40 In Figure 1, wherein is shown my invention as applied to a ring spinning frame, reference numeral 7 indicates a ring rail on which is mounted a ring 8 around which rotates a traveller 9 in the twisting, winding and traversing of the yarn

45 11, coming from any suitable supply package (not shown), on to a bobbin 12. The bobbin is mounted on a spindle 13 which is reduced at its upper or free end to form a seat 14. An abrasive disk 15, which may comprise a hard finely serrated metal, emery or, preferably, carborundum, and which has an opening therein, is positioned on said seat 14 for movement with said spindle. Preferably the abrasive disk is adapted to be 50 freely rotatable relative to spindle 13 for a pur-

pose hereinafter explained. The extreme end of spindle 13 is screw-threaded as shown at 16 to receive a threaded nut 17 which is preferably streamlined as shown and is adapted to retain a floating ring 18 on the reduced portion of spindle 13. The floating ring 18 is adapted to be freely rotatable about spindle 13. To prevent wear upon floating ring 18 due to accidental contact with abrasive disk 15 when, for example, the 10 yarn breaks or fails and the spindle is not stopped immediately, there is provided a disk 19 of cardboard, wood, metal or other suitable material which rests upon abrasive disk 15.

The yarn 11 is delivered, from any suitable 15 source of supply, substantially in a line with the axis of the spindle, is passed through floating ring 18, over the flange 21 of bobbin 12 and through traveller 9 on to the bobbin 12. As the 20 spindle rotates the yarn 11 comes into contact with abrasive disk 15 with what may be termed a complex motion. This is due to the fact that the yarn 11 in rotating about the spindle at the 25 speed of the traveller which is smaller than the rotation of the spindle by the amount necessary to wind the yarn on to the bobbin gives to the 30 yarn a rotating contact with the abrasive disk 15. Now because the floating ring 18 has a larger 35 internal diameter than the diameter of spindle 13 it does not rotate concentrically with the spindle, and this non-concentric rotation plus the forward friction of the yarn against the ring produces undulations or fluctuations of rhythmic periodicity causing intermittent contact with the abrasive disk. This contact with the abrasive 40 disk cuts the filaments of which yarn 11 is composed at frequent intervals giving a staple effect to the yarn. The twisting operation binds in the free ends of the cut filaments.

As is noted above the abrasive disk 15 is preferably freely rotatable relative to spindle 13 or, in other words, it is a floating abrasive disk which is not driven by the spindle. This arrangement serves the purpose of facilitating the starting up and cutting down the resistance to rotation of the 45 yarn around the bobbin. It is important to control the angular path of the yarn over the abrasive disk. Certain combinations of yarn size, twist, spindle speed, ring size, traveller weight, etc., may result in a substantial variation in the 50 angular path of the yarn and thereby result in a variation in contact between the yarn and the abrasive disk and may even result in the yarn failing to contact the abrasive disk. To overcome this it is preferable either to set the conditions 55 so that the yarn is substantially in contact with the flange 21 of the bobbin throughout the run of the bobbin or to install above the bobbin so that it rests on flange 21 a disk 22 which is greater in 60 diameter than the diameter of flange 21 and having sufficient diameter to maintain contact with the yarn throughout the run of the bobbin.

The abrasive disk 15 is substantially circular at a plane at right angles to the axis of the spindle. However, it may depart from said circular 65 shape but only to such an extent that the properties of process uniformity and stability will not be lost. For example, the abrasive disk may be elliptical in shape providing that it does not cut the yarn completely through. The actual 70 surface contact between the yarn and the abrasive disk may be varied by providing the abrasive disk with a sharp, blunt or sloping edge depending upon the amount of filament cutting and the characteristics of the yarn operated upon.

75 The device shown in Figure 3 is also applied in

connection with a ring twisting or doubling frame. In this modification the abrasive disk is positioned on spindle 13 by means of a collar 23. The yarn 11 on its rotation about the spindle is caused to contact the abrasive disk by means of rings 24 5 and 25. These rings are accurately positioned with respect to the abrasive disk 15 so that the desired contact of the yarn with the abrasive disk is maintained. The rings are locked to the main frame work of the machine and they are preferably hinged for lifting upwards during doffing of the bobbin.

In Figure 4, the floating abrasive disk is shown provided with a mounting 26 to which are affixed small vanes or paddles 27. By this construction 15 or arrangement the abrasive disk 15 may be caused to rotate with or counter to the rotation to the spindle 13 at a substantial differential in speed by means of a blast of air or other fluid medium directed against the vanes or paddles 27 20 through pipe 28 or other suitable conduit.

The arrangements shown in Figures 1, 3 and 4 are all concerned with the down-stroke method of operating which has the advantage of applying the device of my invention to doubling operations where doubled or plied yarns are desired. However, my device may be applied to up-stroke twisting as evidenced by the arrangement shown in Figure 6. In this modification the bobbin 12 is rotated at the desired speed and the yarn 11 30 is led therefrom to take-up bobbin 29 which is caused to rotate at such a speed that the required amount of twist is inserted in the yarn. The yarn is led through floating ring 18 and in contact with the abrasive disk 15 and the nut 17, in 35 a manner similar to that shown in Figure 1, on its way to take-up bobbin 29. The path of the yarn over the abrasive disk is controlled by flyer 31 which has a collar 32 seated on flange 21 of the bobbin 12, which flyer is freely rotatable with 40 respect to spindle 13 and bobbin 12.

Other modifications of my invention will readily present themselves to those skilled in the art. For example, the abrasive disk 15 of, say, Figure 1 may be mounted on a compound spindle, that 45 is, the spindle may be hollow and have extending vertically therethrough another spindle. The outer or hollow spindle may carry the bobbin while the inner spindle may have seated thereon the abrasive disk and carry the floating ring 18 50 and retaining nut 17. The two spindles may be driven at different speeds so as to increase or decrease the speed of the yarn in its rotation around the spindles and in contact with the abrasive disk. This arrangement may be further 55 modified by causing the inner spindle to move up and down in a controlled manner so that the abrasive disk may contact with the yarn periodically, thus producing a periodic broken filament effect.

While I have described the yarn as being delivered to the device of my invention substantially in a line with the axis of the spindle, I may feed the yarn to the floating ring 18 at a substantial 65 angle to the axis of the spindle. Thus, I have found that quite substantial angles, such as an angle of 30° from the vertical, when the spindle rotates on a vertical axis, may be employed without loss of running efficiency and stability. Such 70 modification of angle increases the rhythmic movement of the floating ring 18 and otherwise increases the force of contact between the yarn 11 and the abrasive disk 15. Obviously, the angle of the yarn feeding to the spindle may be caused 75

to vary to produce novel and varying broken filament effects.

It is to be understood that the foregoing detailed description is given merely by way of illustration and that many variations may be made therein without departing from the spirit of my invention.

Having described my invention, what I desire to secure by Letters Patent is:

- 10 1. Process for the production of stabilized yarn which comprises drawing a yarn comprising a bundle of filaments longitudinally past a rotating cutting element and imparting to said yarn a complex motion including, in addition to its longitudinal motion, a rotating motion about the axis of said cutting element and a radial oscillating motion towards and away from said axis whereby the yarn has intermittent effective contact with said cutting element which causes the severing of the filaments at frequent intervals along the length of said bundle, thereby transforming at least some of the filaments of the bundle into fibers and imparting a fibrous character to the yarn.
- 15 2. Process for the production of stabilized yarn which comprises drawing a yarn comprising a bundle of filaments longitudinally past a rotating cutting element and at an acute angle to said cutting element, and imparting to said yarn a complex motion including, in addition to its longitudinal motion, a rotating motion about the axis of said cutting element and a radial oscillating motion towards and away from said axis whereby the yarn has intermittent effective contact with said cutting element which causes the severing of the filaments at frequent intervals along the length of said bundle thereby transforming at least some of the filaments of the bundle into fibers and imparting a fibrous character to the yarn.
- 20 30 35 40

40 3. Apparatus for the production of stabilized yarn comprising, in combination with a rotatable spindle, a cutting member mounted on said spindle and means, including a ring approximately co-axial with said spindle but free to move slightly eccentrically of the axis of said spindle, for bringing yarn composed of a bundle of filaments into intermittent cutting contact with said cutting member whereby different filaments of said bundle are cut at different points along the length thereof and a fibrous character is imparted to the yarn.

45 50 55 60 65 4. Apparatus for the production of stabilized yarn comprising, in combination with a rotatable spindle, a cutting member mounted on said spindle and means, including a ring mounted on said spindle and approximately co-axial with said spindle but free to move slightly eccentrically of the axis of said spindle, for bringing yarn composed of a bundle of filaments into intermittent cutting contact with said cutting member whereby different filaments of said bundle are cut at different points along the length thereof and a fibrous character is imparted to the yarn.

70 75 5. Apparatus for the production of stabilized yarn comprising, in combination with a rotatable spindle, a cutting member mounted on said spindle and means, including a ring mounted on said spindle and having a larger diameter than the spindle on which it is mounted, for bringing yarn composed of a bundle of filaments into intermittent cutting contact with said cutting member whereby different filaments of said bundle are cut at different points along the

length thereof and a fibrous character is imparted to the yarn.

6. Apparatus for the production of stabilized yarn comprising, in combination with a rotatable spindle, a cutting member mounted on said spindle, means, including a ring mounted on said spindle and having a larger diameter than the spindle on which it is mounted, for bringing yarn composed of a bundle of filaments into intermittent cutting contact with said cutting member whereby different filaments of said bundle are cut at different points along the length thereof and a fibrous character is imparted to the yarn and means for retaining said ring on said spindle.

7. Apparatus for the production of stabilized yarn comprising, in combination with a rotatable spindle, an abrasive disk mounted on said spindle and means, including a ring mounted on said spindle and having a larger diameter than the spindle on which it is mounted, for bringing yarn composed of a bundle of filaments into intermittent cutting contact with said abrasive disk whereby different filaments of said bundle are cut at different points along the length thereof and a fibrous character is imparted to the yarn.

20 25 8. Apparatus for the production of stabilized yarn comprising, in combination with a rotatable spindle, an abrasive disk mounted on said spindle and adapted to be movable relative thereto and means, including a ring mounted on said spindle and having a larger diameter than the spindle on which it is mounted, for bringing yarn composed of a bundle of filaments into intermittent cutting contact with said abrasive disk whereby different filaments of said bundle are cut at different points along the length thereof and a fibrous character is imparted to the yarn.

9. Apparatus for the production of stabilized yarn comprising, in combination with a rotatable spindle, an abrasive disk mounted on said spindle, means for moving said abrasive disk relative to said spindle, and means, including a ring mounted on said spindle and having a larger diameter than the spindle on which it is mounted, for bringing yarn composed of a bundle of filaments into intermittent cutting contact with said abrasive disk whereby different filaments of said bundle are cut at different points along the length thereof and a fibrous character is imparted to the yarn.

10. Apparatus for the production of stabilized yarn comprising a rotating cutting member, means for drawing a yarn comprising a bundle of filaments longitudinally past said rotating cutting member and means for imparting a complex motion including, in addition to its longitudinal motion, a rotary motion about the axis of said cutting member and a radial oscillating motion towards and away from said axis whereby the yarn has intermittent effective contact with said cutting member so that different filaments of said bundle are cut at different points along the length thereof and a fibrous character is imparted to the yarn.

60 70 75 11. Apparatus for the production of stabilized yarn comprising a rotating cutting member, means for drawing a yarn comprising a bundle of filaments longitudinally past said rotating cutting member and at an acute angle to said cutting member, and means for imparting a complex motion including, in addition to its longitudinal motion, a rotary motion about the axis of said cutting member and a radial oscil-

lating motion towards and away from said axis, whereby the yarn has intermittent effective contact with said cutting member so that different filaments of said bundle are cut at different points along the length thereof and a fibrous character is imparted to the yarn.

12. Apparatus for the production of stabilized yarn comprising a rotating abrasive disc, means for drawing a yarn comprising a bundle of filaments longitudinally past said rotating abrasive disc and means for imparting a complex motion including, in addition to its longitudinal motion, a rotary motion about the axis of said abrasive disc and a radial oscillating motion towards and away from said axis, whereby the yarn has intermittent effective contact with said abrasive disc so that different filaments of said bundle are cut at different points along the length
13. Apparatus for the production of stabilized yarn comprising a rotating abrasive disc, means for drawing a yarn comprising a bundle of filaments longitudinally past said rotating abrasive disc and at an acute angle to said abrasive disc, and means for imparting a complex motion including, in addition to its longitudinal motion, a rotary motion about the axis of said abrasive disc and a radial oscillating motion towards and away from said axis, whereby the yarn has intermittent effective contact with said abrasive disc so that different filaments of said bundle are cut at different points along the length thereof and a fibrous character is imparted to the yarn.

WILLIAM WHITEHEAD.
